JOHN E. BUCHER, OF COVENTRY, RHODE ISLAND, ASSIGNOR TO NITROGEN PRODUCTS COMPANY, OF PROVIDENCE, RHODE ISLAND, A CORPORATION OF RHODE ISLAND.

METHOD OF FIXING NITROGEN.

1,120,682.

Specification of Letters Patent. Patented Dec. 15, 1914.

Application filed November 7, 1913. Serial No. 799,798.

To all whom it may concern:

Be it known that I, JOHN E. BUCHER, a citizen of the United States, residing at Coventry, in the county of Kent and State of Rhode Island, have invented certain new and useful Improvements in Methods of Fixing Nitrogen, of which the following is a specification.

This invention relates to the fixation of nitrogen and more particularly to improvements in the processes described in my pending applications for United States Letters Patent, respectively designated Serial No. 726,924, filed October 21, 1912, and Serial No. 737,368 filed December 18, 1912.

In operating my former processes upon a larger scale I encountered certain difficulties which will be hereinafter more fully referred to and the method and means for avoiding or overcoming which I have herein set forth with such particularity as to enable those skilled in the art to practise my invention.

The present process while involving broadly the provision of the extended catalytic solution surface particularly referred to in my said application Serial No. 726,924, does so in a novel manner, preferably through the instrumentality of what may properly be termed briquets. These briquets when made of the preferred substances, are of necessity of such a nature that while they may be made sufficiently firm and resistant to rupture or distortion at ordinary temperatures, they are nevertheless softened by the heat of the nitrogen fixing operation so as to become plastic; and provision is preferably made for restoring firmness to said briquets after the cyanogen compound sought has been formed therewithin. I have also found that the process is very materially favored by pre-heating the gaseous material, *e. g.* free nitrogen, as well as the solid material, *e. g.*, the briquets themselves; the latter advantageously containing all of the elements requisite for the reaction except the nitrogen, and further by introducing certain kinds of said gaseous material in a particular manner, as hereinafter described. Indeed in certain phases of my process it becomes a matter of the greatest importance as to where the gases enter the charges in the retorts and under what conditions they escape from these charges. It is highly desirable to pro-

vide a ready access of both nitrogen and adequate heat to the whole of the catalytic solution surface, which latter may be made to permeate the entire mass. I have also aimed to provide a process using but few and inexpensive materials, preferably such as sodium carbonate, coke and producer gas, or the equivalent of such substances.

Having thus briefly indicated the nature and objects of the present invention I will now set forth the particulars thereof so that by carefully following the prescribed conditions thoroughly consistent results may be attained.

As in my previously described processes I contemplate fixing nitrogen by effecting a reaction between free or atmospheric nitrogen, an element capable of acting as the base of a cyanogen compound such as a cyanid, and carbon, in the presence of what may be termed a catalytic material, such as iron or the like, which is capable of dissolving or combining with the carbon to render it reactive under the conditions of the operation. The catalyzer should have a greatly extended surface in proportion to its bulk and the carbon should be supplied thereto so freely as to maintain a high content of the same in solution in said surface despite the more or less continuous removal of said carbon therefrom during the course of the operation.

The preferred catalytic material in my process described in my said application Serial No. 726,924 was iron in finely pulverulent condition, this being most intimately mixed with powdered carbon, *e. g.* graphite, and preferably also directly with a suitable source of alkali metal or of some equivalent metal or element, *e. g.* sodium or barium carbonate, the reaction being preferably effected at a temperature below the eutectic point of the carbon-containing iron or other like acting catalytic material. The preferred catalytic material herein, as in my previously described processes, is iron, on account of its efficiency and relatively low cost; but while I prefer to use iron, I do not desire to be limited thereto since I am aware that such elements as chromium, manganese, nickel, cobalt, and even certain elements entirely foreign to the iron group, may be used.

In the present process the mixture of reactive and catalytic materials is subjected

to treatment to form the same into briquets having certain definite characteristics which particularly adapt them to a commercial process; and the preparation of the materials for participation in the process actively or catalytically, as the case may be, will now be described, the description being in accordance with actual practice.

Preparation of the iron.—Over a thousand 10 pounds of iron were prepared by grinding portions of commercial cast iron in a suitable ball mill containing iron balls, until the iron was fine enough to pass through a sixty mesh sieve, or even finer. This iron gave 15 reasonably good results when used in the process in a mixture containing two parts of iron, two parts of coke and one part of soda ash; the product sought being in this case sodium cyanid. A portion of the so prepared 20 iron was ground finer and it then gave excellent results in such a mixture as the above; the cyanid resulting from the subjection of the iron-coke-soda ash mixture to a proper temperature, such as is herein- 25 after referred to, being separated from the residues of the reaction by lixiviation. The said residues consisted, of course, of a mixture of iron and coke and were most advantageously used over again in the process by 30 grinding the mixture preferably for from two to five hours in the mill. As the grinding of commercial cast iron turnings to the required fineness was found, with the grinding apparatus available, to be a tedious operation, I have found it desirable to use 35 commercial iron scale when operating with large quantities.

For the above work over three tons of the scale were readily ground in what is known 40 as an Abbe mill to a fineness such that about 99 per cent. passed through a sieve of 100 mesh to the inch. This powder was then mixed with ground coke, usually, in the proportion of 70 pounds of scale to 80 pounds 45 of coke for each charge for the mill. The grinding of such a charge is usually preferably continued for several hours and it is then mixed with soda ash, commonly in the proportion of 200 pounds of the iron-coke 50 mixture to 40 pounds of soda ash. This last mixture was then either heated with nitrogen to produce both cyanid and metallic iron, or without nitrogen, to produce metallic iron alone, as desired. In either case 55 the so prepared mass was thoroughly lixiviated by washing in lots of 800 to 1000 pounds on a vacuum filter. It was again dried and again ground for four or five hours in the mill. The iron-coke mixture so 60 produced was extremely reactive and afforded a cheap and easy way of producing the greatly extended catalytic solution surface referred to in my said patent application.

65 The coke which I have heretofore used,

contained about seven per cent. of ash; and the iron scale, containing some oil, was used just as it came without being separated magnetically or otherwise from the three per cent. or more of sand and pebbles with 70 which it was contaminated. Neither oil, ash, mineral matter or sulfur in the materials used seemed to affect the subsequent operations in any very noticeably deleterious way; a feature, it should be noted, of value. 75

After the above materials have been used once and have been lixiviated thoroughly, the cyanid produced in subsequent operations no longer gives a black sulfid precipitate with silver nitrate upon titration but 80 the precipitated silver cyanid is pure white in color.

Nearly all of the work described below in which metallic iron was used, was done with a mixture of about equal parts of iron and coke prepared as above specified; while all of the herein described operations in which iron scale was used instead of metallic iron, were carried out with the mixture having about the proportion of 70 parts of scale to 85 80 parts of coke.

Preparation of briquets.—In the first of my co-pending applications above referred to, it is shown that cyanid formation takes place very rapidly when the charge is used 95 in the form of powder and in thin layers, but when it is used in thicker layers in iron pipes, action is much slower because the nitrogen has to penetrate through a thicker layer of charge. Also, the charge of powder 100 shrinks considerably in bulk when the alkali carbonate, or its equivalent, melts; so that a deep channel is formed and the rapid current of nitrogen containing gases flows over the top of the charge and penetrates 105 into the interior thereof but slowly. I have found that in operating with a pulverulent charge disposed in horizontal tubes 10 feet long by 2 inches in diameter, the absorption of nitrogen is quite rapid at first, but it then 110 becomes slower and may take about two and one half hours to obtain a residue which when lixiviated gives a solution which titrates for sodium cyanid of substantially 115 100% purity and which gives no precipitate with calcium chlorid; such absence of precipitate, of course, indicating the absence of sodium carbonate. When the charge is heated in vertical tubes or other suitable containers and the nitrogen is passed into 120 the base of the charge itself, preferably through a number of suitable small openings, it causes the formation of small tubular channels or flues in the mass while at the same time largely, if not indeed entirely, 125 preventing the geyser-like action, herein-after referred to, before the mass becomes plastic by the melting of the alkali compound, or the equivalent of such compound.

I may here state that I am aware that 130

various other materials than sodium carbonate are adapted for use in my process. Thus, barium carbonate may be employed and indeed practically all of the carbonates and hydrates of the alkali metals and many of the corresponding or like compounds, of, for example, the alkaline earth metals; the essential thing to be observed being that some metal or element, *e. g.* sodium, be supplied, preferably from a convenient source of the same such as the carbonate of sodium; the said metal or the said compound thereof to be capable of participating in the cyanogen-compound-forming reaction, under the conditions of the operation, and of acting as the base of a stable cyanogen compound under said conditions.

Vertical tubes or retorts are usually far more effective than horizontal ones, because the nitrogen current is more readily made to penetrate into the interior of the charge rather than to simply pass over it, or at most, to penetrate but little thereinto.

The flues in the charge above referred to, may also be made by thrusting wires through the mass; especially after it has become plastic, and obviously the introduction of nitrogen may be effected in many ways. Preferably, however, nitrogen is introduced under a light but positive pressure, so that there is no gradual compression of a considerable volume of this gas followed by subsequent more or less explosive or geyser-like actions as the charge confining the gas gives way. It is hence more over advantageous to use the charge in briquetted form to avoid the disadvantages inherent in the use of powders, since with the latter there is a liability to clogging of the small openings which admit the nitrogen; or even of clogging of the retort or large tube itself, with the consequent disturbance of the process; while, further, a sintered charge in the retort may be somewhat difficult to remove.

Upon trial of powdered charges of the above description, in continuously acting furnaces of the type hereinafter described, the difficulties were found to be much greater than were subsequently encountered when briquetted charges were used; while further with the powder, under mechanical force, including the action of gravity, the heated charge became compacted or gradually briquetted so that after cooling, it was very difficult to remove it with an iron chisel and hammer. This behavior of the powdered charge showed the possibility of briquetting the iron-coke-soda ash mass at a temperature above the melting point of the soda ash; and accordingly an iron pot was filled with the reactive mixture containing one part each of iron-coke and soda ash; the pot being covered to exclude air as much as possible. It was then heated to redness

(about 900° C.) and the plastic mass was pressed firmly with an iron pestle. The resulting briquet, in which a little cyanid had already been formed by slight contact with the air, was found after cooling, to be very firm and adapted to be handled or even thrown about without breaking.

Experiment 1: This briquet was then broken into coarse fragments and heated in a current of nitrogen in a one half inch iron tube, to 1000°-1060° C., for 10 minutes. The evolution of carbon monoxid was very rapid at first but had practically ceased at the end of this short time. After cooling, the briquet fragments were lixiviated and the so obtained solution titrated for sodium cyanid of 100% purity and gave no precipitate with calcium chlorid. The titration showed these briquet fragments to contain 7.4% of sodium cyanid.

Experiment 1 showed that briquetting for cyanid work could be done without the addition of any foreign binder, such as tar or the like; the alkali compound, or its equivalent, itself acting as the binding material, and that the briquetting could be effected at a relatively high temperature; thus dispensing with the addition of water to get the required plastic condition and avoiding the expense of subsequently again evaporating this water. Briquets thus prepared can be charged into the furnace before they have cooled, or they may even be made directly in a suitable cyanid-producing furnace; thus giving the added advantage of handling the charge preheated to the temperature of cyanid formation substantially at the time of its introduction into the reaction zone of said furnace. Also, pressing of the hot plastic mass causes a great decrease in volume and hence must give closer contact of the iron and coke particles, or the equivalents of these materials; thus aiding in producing and maintaining a most efficient catalytic solution surface. The very rapid formation of cyanid under these prescribed conditions shows great efficiency and it also admits of particularly free access of nitrogen to the interior of the charge through the interstices between the individual briquets; an advantage which can scarcely be over estimated.

The fact that in the just cited experiment, the 7.4% of sodium cyanid (theory about 37%) in the briquets represents practically all of the alkali compound left in the mass, demonstrates the very greatly increased volatilization of the alkali compounds (and of course in like manner of their equivalents) owing to the large exposure of surface from which evaporation can take place. This not only aids cyanid formation and gives a high purity; but facilitates the removal thereafter of the cyanid from said briquet by vacuum distillation when the latter is

used in accordance with the disclosure in my said patent application Serial Number 737,638; because of greater initial purity and by reason of the increased evaporation 5 surface. The use of briquets is also especially advantageous in case the cyanid is to be recovered by lixiviation. The reactive materials thus briqueted make it possible to avoid the use of the dust-like powder and 10 they may hence be most easily handled in the continuously acting furnaces hereinafter described.

Notwithstanding the advantages of the process involving briquetting at a high temperature, I deemed it desirable to work out 15 a method making use of liquids, such as water, to secure the plasticity requisite for briquetting. Such a method would be more easily carried out with machinery which 20 is already available commercially, and it would be very well adapted for use wherever cyanid was to be extracted by lixiviation; while briquets were made conveniently as follows: 320 pounds of iron-coke mixture as 25 it came from the mill was mixed with 80 pounds of sodium carbonate. Water sufficient to give the desired consistency was then added to the charge in the said mixer and 30 or 40 additional turns were given. 30 This warm dough-like mass was then preferably briqueted immediately. The quantity of water required varies very considerably 35 with the initial temperature of the substances; the quantity of soda ash in the mixture, the promptness with which it is briqueted, the temperature of the water, which in some cases may advantageously be supplied as steam, etc. The briquetting itself was done with a small power driven meat 40 grinder having a steel disk $3\frac{1}{2}$ inches in diameter which contained 37 circular holes of $\frac{1}{4}$ inch diameter. The knife inside of the grinder was removed and one having but a single blade was placed outside of the 45 steel disk so as to cut the briquets into lengths of about one inch. The briquets used were hence cylinders each about one inch long by $\frac{1}{4}$ inch in diameter. It may further be found advantageous to use perforated briquets the surfaces of which may 50 also be fluted, since this will obviously facilitate the penetration of the nitrogen thereto. The moist mass of material may also be briqueted at a higher temperature, 55 and even above 100° C., if desired, the water being added hot, or as previously intimated, in the form of steam. The use of hot water and particularly of steam in certain cases permits of the use of less water and in any 60 case the briquets will harden more quickly and require less heat for drying. The briquets could be made in other forms and shapes than cylindrical and of sizes other than that indicated, but the so produced cylindrical ones were used in all of the herein-

after described experiments where briqueted material was employed, and were found to be eminently satisfactory. The drying of the briquets is an important matter. If they are placed in a deep layer at the ordinary 70 temperature for several days, they practically fall to powder when they are disturbed. If, however, they are dried more quickly over a steam coil they become very hard and firm and give practically no dust 75 on handling.

About one ton of briquets was prepared in the same general way from the scale-coke mixture of the composition above set forth; said mixture being admixed with soda ash, 80 and I have noted that while these scale briquets were reasonably firm, they showed more tendency to disintegrate, especially at the temperature of cyanid formation, than those made from metallic iron. 85

Further experiments with briquets.—For purposes of comparison, the following Experiments 2, 3, 4 and 7 were made with 50 pounds of alcoholized iron Ph. G. IV, ground with 50 pounds of pulverized coke 90 for 5 hours in the mill. This mixture was briqueted moist with different proportions of soda ash.

Experiment 2: Here, 150 grams of iron-coke-soda ash was briqueted in the ratio 95 respectively of 2:2:1 and the mass was heated in a horizontal 1 inch pipe in a current of nitrogen for 6 minutes at from 600° to 900° C. The escaping gases were ignited at 600° C. and at 700° C. they were burning very 100 finely. The greater part of the action was apparently over in 15 minutes; during 105 which the temperature rose from 600° C. to 1000° C. Upon cooling and lixiviating, the briquets were found to contain 13.7% of sodium cyanid of 85% purity.

Experiment 3: In this case 10 pounds of the iron-coke mixture used in Experiment 2 was mixed with 5 pounds of soda ash to 110 make a 1:1:1 mixture and briqueted with 1500 cc. water. A 150 gram lot of these dry briquets was heated in a current of nitrogen in a 1 inch horizontal iron tube, at from 600° C. to 1030° C., for 30 minutes. Here the evolution of combustible gases was 115 considerably slower than in Experiment 2 and occurred mostly in the 25 minutes during which the temperature was rising from 600° C. to 1020° C. The resulting briquets which were quite hard and perfect, contained 20% 120 of sodium cyanid of 95% purity.

Experiment 4: In this case $7\frac{1}{2}$ pounds of the iron-coke mixture used in Experiment 2 was mixed with $7\frac{1}{2}$ pounds of soda ash and 125 briqueted moist to make a 1:1:2 mixture containing 50% of soda ash and 150 grams of these briquets were heated in a horizontal 1 inch iron pipe in a current of nitrogen for 1 hour at from 600° C. to 1090° C. The combustible gas evolved sluggishly 130

during the entire time. Upon cooling, the mass was found to contain 14% cyanid of 80% purity.

Experiment 5: This experiment was made to test the efficiency of a 900 pound lot of the 2:2:1 iron-coke-soda ash briquets which were prepared from a ground cast iron-coke mixture which had been used and re-used several times for cyanid preparation as above described. Here, 150 grams of the briquets were heated in a horizontal 1 inch pipe in a current of nitrogen at from 680° C. to 960° C. for 15 minutes. The evolution of carbon monoxid was very pronounced at 680° C. and continued vigorously for about 5 minutes during which the temperature rose to 870° C.; while in 5 minutes more the temperature had reached 900° C. and the reaction had become quite slow. The residue of very hard briquets contained 15% of sodium cyanid of 85% purity.

Experiment 6: This experiment was a duplicate of Experiment 5 except that the temperature was further allowed to rise to 1010° C. and the time of heating was somewhat longer. The action was largely over, even before 860° C. was attained, at which temperature observations began. The briquets, upon analysis, were found to contain 16.4% of sodium cyanid.

In Experiments 5 and 6, the nitrogen absorption was so rapid that I had scarcely any time to make records of the changes taking place, and the reaction was in large measure completed in less than 10 minutes and before the temperature had reached 900° C.

The preceding experiments were all made in 1 inch iron pipes where the heat and the nitrogen would have ready access to the interior of the charge of briquets.

Experiment 7: In two 6 inch horizontal pipes charged with 180 pounds of very good 2:2:1 iron-coke-soda ash briquets only 4 to 8% of sodium cyanid was obtained in the residue even upon heating for a number of hours at a temperature favorable for cyanid formation. As a further test, 25 pounds of good 2:2:1 briquets from the same lot that was used for Experiment 2 were heated in a current of nitrogen in a 6 foot piece of a 6 inch horizontal pipe at a temperature ranging from 1000° C. to 1080° C. for about one hour and twenty minutes; and upon cooling and examining the charge it was found to have settled so that there was a channel about $\frac{1}{2}$ inch deep in the upper part of the tube. The vertical section at the end where the nitrogen entered had a sodium cyanid content of 9.5%, while the vertical section about one quarter way through this end of the charge averaged only 3.5% of cyanid. The vertical section taken from the middle of the charge showed a cyanid content of 12.5%

in a narrow layer at its top, where the nitrogen current passed over it, and about 3% in the broad intermediate layer; while at the bottom of this section only 1.4% of sodium cyanid was found. This is illustrated diagrammatically in Fig. 7 and it shows the average cyanid content of the entire charge to be very low. Evidently the settling of the charge formed a channel, so that the nitrogen could pass therethrough over the top of the charge and not to any material extent through it, and this action was probably greatly intensified by the counter currents of carbon monoxid which flowed upward through the charge. Experiments with 20 pound charges of iron-scale-coke soda ash in this horizontal 6 inch tube gave similar results.

Experiment 8: In this experiment the same 6 foot long, 6 inch diameter iron pipe was charged with briquets as before, but was placed in a vertical position in the furnace. In this case 50 pounds of 1:1:1 iron-coke-soda ash briquets were heated in the nitrogen current, entering at the bottom of the pipe, for 1 hour and 10 minutes at from 1000° C. to 1090° C. The reaction was not completed when the experiment was stopped, but even so, the top of the charge contained 24% of sodium cyanid while the bottom contained 20%. This shows conclusively that the vertical pipe acts very efficiently even when its diameter is 6 inches. It is also evident that 10 pounds of sodium cyanid can be produced, per run, efficiently in a 6 foot tube of this diameter.

Experiment 9: In this case 55 pounds of briquets composed of about 22 pounds of iron scale, 24 pounds coke, and 9 pounds of soda ash were heated in a nitrogen current in the vertical 6 inch pipe, as in Experiment 8, for 2 hours at from 1000° C. to 1100° C. Action at the end of this time was slow and incomplete. The tube was then allowed to cool and small sections, taken at different levels, were examined. The top section contained 28% of sodium cyanid of 87% purity; other sections from the top to the bottom contained respectively 16, 14, 12 and 10% of cyanid; the purity of these four sections varying from 90% to 93%. The central part of the lower section contained moderately firm hard briquets whose cyanid content was 12% of substantially 100% purity; while the outside part of this lower section was partly disintegrated and contained only 7% of sodium cyanid. This change in concentration of, for example, alkali compounds is very important and is shown diagrammatically in Fig. 6. In this experiment, all, or nearly all, of the required heat was supplied to the charge on the outside and consequently much volatilization of the alkali material took place in the hotter outer layers; resulting in a disintegrating of these

layers as the alkali volatilized; while the inner part of the section, which was firmer, contained more alkali. The experiment, besides showing the application of briquetting to a method of fixing nitrogen, and if desired, of simultaneously producing pure iron, is also of great importance in showing the conditions necessary for efficient effectuation of the process in a continuously acting furnace.

Experiment 10: A vertical 4 inch iron pipe was used and a pyrometer contained in a $\frac{1}{2}$ inch iron pipe was pressed into the center of the charge which was composed of 8 pounds of 2:2:1 iron-coke-soda ash briquets. When the pyrometer in the outer furnace read 1030° C. the inner one read 150° C. In 40 minutes more the outer one read 1080° C. while the inner indicated 880° C. It then took about 20 minutes more for the inside temperature to rise to 1010° while the outer reading remained constant. This shows the slow rate of heat penetration through the charge and it also shows the variations in action caused by varying the rate of flow of nitrogen. In this experiment when the heat was stopped, the product was found to contain 17% of sodium cyanid of 99% purity.

Experiment 11: A 1 inch iron tube was charged with 150 grams of coke and then 150 grams of iron scale-coke-soda ash briquets of the composition used in Experiment 8 was introduced. The two layers of the above materials were kept separate by using gauze screens and the tube was then heated in a horizontal furnace from 910° C. to 1010° C. for 30 minutes and a current of air was passed into the end of the tube containing the coke. The process so conducted was found to be fairly efficient as the briquets contained 12.7% of sodium cyanid of about 70% purity. Upon lixiviation, they yielded a clear aqueous solution, showing no yellow color and no lampblack-like carbon floated upon the water. The yield was as good as that which I had obtained when using nitrogen gas, prepared by passing air over hot copper, with these briquets.

It may be well to note here that all temperatures referred to in this specification were measured with a thermo-electric pyrometer, placed near the pipes in which the reaction was taking place.

The above experiments also show the desirability of using a continuously acting furnace for the briquets which become plastic at the temperature of cyanid formation; together with the co-acting advantage, so to speak, of so disposing the material that primarily gravity, or its equivalent, lateral pressure, shall aid in maintaining an efficient distribution of the nitrogen current throughout the bulk of the reactive mass, in contradistinction to so disposing the said

reactive mass that the unopposed action of gravity by causing settling of the same will open unduly large channels for the escape uselessly of the said nitrogen current, as shown in Experiment 7 and Fig. 7.

In general, the furnace construction should permit, in part at least, the transformation of the carbon monoxid formed in the cyanid producing zone, into carbon dioxide within the charge itself in such a way as to utilize the extra heat thus produced by the formation of carbon dioxide while at the same time avoiding the deleterious effect of the latter gas upon the cyanid. It should also avoid the loss of alkali or the like and the consequent disintegration of the briquets at one place and the flooding with the alkali, or like compounds, of portions of the catalytic solution surface at another place or places; while nevertheless retaining the great advantage of rapid circulation of the said alkali or its equivalent. In connection with these last mentioned features attention may again be directed with advantage to Experiment 9 and also to Fig. 6 of the drawing.

In the drawings which form a part hereof and in which like reference characters designate like parts throughout the several views I have exemplified certain preferred furnace construction which are adapted for the effectuation of my process in accordance with the above described conditions. I am aware, however, that various changes and modifications may be made in the furnace construction whereby to differently establish the prescribed conditions for effectuating my commercial process; and I am also aware that various minor changes and modifications may be made in the manner of effectuating the process itself without departing from the spirit of my invention. I hence desire to be limited only by the scope of the claims appended hereto; said claims being broadly construed in the light of my disclosure.

Drawings.—Referring now to the drawings, in which like characters of reference designate like parts: Figure 1 is a vertical section of a muffle furnace provided with a retort within which the cyanid forming reaction may be effected. Fig. 2 is a detail transverse section taken on line II—II of Fig. 1. Fig. 3 is a detail vertical section taken on line III—III of Fig. 1. Fig. 4 is a perspective view of a fragment of a double walled or annulus-like retort which may be employed in connection with my process. Fig. 5 is a somewhat diagrammatic vertical section of a modified furnace construction. Fig. 6 is a diagram showing the possible change of alkali concentration in a charge. Fig. 7 is diagrammatic or graphic representation of the cyanid formation in a large round horizontal retort.

The retort 1, shown in Figs. 1, 2 and 3 may be of cast iron and is preferably made of a relatively long 8 inch pipe which is flattened down for the greater portion of its length until its interior dimensions are approximately 2 inches by 10 inches in cross section; the bottom of the pipe being left round and the broader walls at the top thereof hence in effect gradually flaring apart as the round lower end is approached; the flare beginning from a point preferably about half way up the pipe. The retort thus formed is admirably adapted to the process since the heat from the oil burners 2 or the like does not have to penetrate any great distance into the bulk of the reactive mass, at the part of the retort to which the heat is most strongly applied, before it has reached the center or core thereof; while the gradual increase in cross sectional area of the vertical retort from the point therein where the material being treated commences to become noticeably plastic, tends to prevent the retort from becoming choked and hence facilitates a continuous feed therethrough. The retort may be centrally disposed in a suitable brick-work furnace 3 which preferably tapers in at about half way up toward the top thereof to form a flue 4 which surrounds the upper part of the retort and preferably conforms in shape thereto; a space of about $1\frac{1}{2}$ inches being provided all around between the retort and the inner walls of the flue. A delivering connection or T 5 may be bolted to the flange at the upper end of the retort 6 inches or more above the brick flue, to provide means for introducing material into said retort. Preferably, a screw conveyer 6 is used to deliver briquetted material through the connection 5; the said material entering the conveyer from a hopper 7.

The oil burners extend through suitable openings in the furnace walls and may have the flames thereof directed toward the retort; it being advisable in such case to provide a baffle or screen 8 of fire brick or other suitable refractory material so as to prevent the direct impingement of said flames against the side or sides of the retort. In the present instance the baffle is substantially tubular with openings 8' in the sides thereof which are away from the flames.

The brick furnace may rest upon a cast iron plate 9 which in turn is supported upon columns 10 so as to provide an air space below the furnace proper into which the gradually rounding or flared lower end 1' of the retort extends. The bottom of the retort is flanged and bolted to the arm of a cast iron T 11 and the lateral arms of this T are respectively bolted to pipe sections 12 and 13 and together with a second T 14, secured to the outer end of pipe 12, constitute a

screw conveyer chamber, the screw 15 of which is mounted upon a shaft 16 journaled at its left hand end in a suitable thrust bearing head 17 and at its right hand end in a head 18 secured to T 14 and provided with a suitable stuffing box 19. The screw, 15 is slowly driven in any desired manner as by means of a chain and sprocket drive 20 and the treated material conveyed thereby from the T 11 is delivered through the 75 preferably downwardly directed arm of the T 14 through a T 21 to a suitable receptacle 22. The cyanid containing material delivered to the latter may be collected therein and removed in bulk or it may be continuously removed by means of a screw conveyer 23; care being preferably exercised when the latter, or its equivalent, is used to prevent any material quantity of air from entering the retort therethrough, since the 80 oxygen content of such air would contaminate the product, e. g. by forming a cyanate or even some carbonate of the element which constitutes the base of the cyanogen compound sought. 90

Samples of the product may be taken off at 24 and the free nitrogen, preferably used, may be introduced through a pipe 25 which delivers to an annular pipe 26 disposed in the enlarged end 27 of the upstanding arm 95 of the T 11. A plate 28 covers the pipe 26 and shields it from the descending mass of briquets and the enlargement 27 affords the free nitrogen, or the like, admitted at this point, a chance to quite freely escape 100 from the downwardly and outwardly directed apertures or vents 29 in pipe 26.

Within the retort 1 in Fig. 2 is shown a mass of briquetted material 30 in course of treatment while the material 31 shown adjacent the screw 15 has of course been subjected to the cyanid producing reaction. 105

It is important to note that the nitrogen delivered to the reactive mass is preheated by its passage through the hot residues of 110 said reaction, and that in like manner the briquets introduced through the hopper 5 are preheated by the escaping gaseous products of such reaction; carbon monoxid and some unconsumed nitrogen constituting the 115 greater part of these gases and escaping, if desired, through the open upper end of the hopper 5.

The chilling of the solid reaction products while passing through the exposed and 120 cooled portion 1' of the retort and further by their contact with the relatively cool current of nitrogen passing up into the retort, is also of value in that it facilitates the removal of said products from the retort, the 125 briquets upon cooling losing their acquired plasticity, while at the same time the nitrogen is preheated.

The preheating of all of the participants of the reaction, when done in the manner 130

indicated, not only saves fuel, but favors the efficiency of the process; the reaction taking place practically as soon as a given bulk of the solid material enters the reaction zone, and throughout the extent of said bulk; a feature of very great importance from a commercial standpoint. This manner of preheating the charge also enables us to make use of the reversible equation:

since, disregarding diluting gases, 96% CO is in equilibrium at 1000°C . while at 500°C . only 5% CO is required for equilibrium, 95% being CO_2 . Evidently, the very finely divided iron and carbon aid as catalysts in establishing the equilibrium. Here, in the limiting case, we have the formation of almost pure CO in the cyanid-forming zone and farther up in the retort it might revert largely to CO_2 thus giving up extra heat to make the process less endothermic while at the same time restoring some carbon to the charge. This would, in so far as it is effected, amount to 25 producing cyanid according to the equation:

Comparison of this equation (2) with the 30 following equation:

which is generally given for cyanid formation, shows these advantages and, the procedure, in any case, has the additional advantages of avoiding the deleterious effect of CO_2 upon the produced cyanids, and of requiring less grinding of carbon because of 40 the smaller quantity consumed.

When iron scale, magnetite, hematite, etc., are used instead of metallic iron in making the briquets, the above effects may also be in evidence, and, in addition the iron oxides 45 will aid in changing the CO to CO_2 in the upper zones of the vertical retort, as for example:

50 thus utilizing the large heat of combustion of carbon to CO_2 . This is especially important when iron scale is used.

It should also be noted that the carbon monoxide produced in the process may be 55 burned to CO_2 in the furnace shown in Fig. 1 or even inside of the tube 32 shown in Fig. 4 or otherwise suitably used in the process; thus in effect giving the reaction for the process as:

This equation shows that the process is now strongly exothermic, that the quantity 65 of carbon required is the same as in equa-

tion (3), that we can very readily get the gaseous product of the reaction substantially quantitatively in the form of CO_2 without any risk of injurious action from this gas.

If it is desired to favor the formation of CO_2 in the manner suggested in equations 2 and 4, the upper part of the retort may be enlarged or else connected with a hopper or reservoir which contains a large quantity 70 of briquets at the proper temperature as indicated in Fig. 5. These briquets (when sodium carbonate is used) will not be hot enough to be plastic, hence they can be handled easily and they will insure a longer 80 contact with the gaseous reaction product and hence a more complete approach to the equilibrium indicated in equation 1.

While pipes with straight walls are adapted for use, I prefer to taper or flare the retort walls so as to gradually increase the cross-sectional area as their lower extremities are approached, to facilitate the substantially continuous downward passage of the charge, and since my experiments and other work have shown that the slow rate 90 at which the heat penetrates to the interior of the charge of briquets is a factor to be considered, even where a round pipe having a diameter of only 4 inches is used, I now 95 prefer to use pipes flattened to afford a more or less rectangular or elliptical cross-section through at least a considerable extent of the length thereof. Such a pipe as I have illustrated in Fig. 1 combines the advantage of easy feeding therethrough possessed by conical or sloping walled pipes, larger at the bottom than at the top, with the advantageous disposition of the reactive material to permit of quick heat penetration 100 to the middle of the still relatively thick bulk of briquets.

By an obvious modification of the arrangement at the base, a continuously feeding furnace with concentric tubes or pipes 32 and 33, forming a retort such as is indicated in Fig. 4, may be constructed, these tubes readily adapting themselves to various modifications along the lines which I have just indicated; the retort proper being substantially annular in cross-section. This form of retort possesses the further advantage that it permits of heating from both within and without so that if the space between the concentric pipes be approximately 2 inches, 110 but about 1 inch of the briquetted material need be penetrated by the heat in order to effect the desired reaction in the innermost portions thereof.

The types of furnaces which make provision for quick heating have a great advantage in that they can be operated at a lower temperature since the rate of cyanid formation is shown by Experiment 10 to be largely dependent upon heat penetration and hence, 120

for a given cyanid output, the temperature of the outside of the pipe or retort holding the charge need not be so high as in furnaces which do not permit of quick heating.

5 Cast iron retorts, it may be here noted, are adapted to easily withstand the operating temperature, which should preferably be maintained below the eutectic point of the catalytic material, saturated, as it is apt to be, and indeed preferably is, with carbon, so that this reactive solution surface may be maintained both physically as a surface and as regards the carbon content thereof, since if the temperature be unduly raised sintering or worse occurs in the body of the solid, and preferably briqueted, material under the treatment.

20 Obviously other substances than iron may be used for cyanid production in the construction of the reaction tubes or retorts; but as I have found iron tubes very durable when heated in a reducing flame to the relatively very moderate temperature required by my process, I prefer to use such tubes on account of their comparatively low cost.

25 *Gases other than pure atmospheric nitrogen available for the process.*—While in certain cases I prefer to use substantially pure nitrogen, as I have indicated I may also use air: burning the oxygen therein, preferably to carbon monoxide before admitting it, or rather the hot residues of such combustion, to the charge to be treated. Further, I have quite successfully employed unpurified producer gas, in place of atmospheric nitrogen, with a continuously acting furnace which contained a reaction pipe 6 inches in diameter by 10 feet long and which moreover did not even have the chimney and hence had no provision for preheating the moving charge either from the hot gases ascending inside or outside of the retort. The producer gas was made by passing air which had not been dried, through coke heated to incandescence in an iron tube and in some cases the so prepared gas contained less than 1% of carbon dioxide. It was led directly, and without purification, to the cyanid producing furnace and was used in the same way as nitrogen. The resulting cyanided briquets were lixiviated and a solution was obtained having a strong yellow color such as I have noticed when working with nitrogen into which inadvertently some oxygen had found its way. Also a scum of lampblack-like carbon was noted, which was apparently due to the deposition of carbon according to the equation:

60 The average cyanid content of the briquets in runs lasting from 6 to 8 hours was about 5%. Compared with the above cited Experiment 11, this showed much damage from the carbon dioxide formed according to the

above equation. This formation of carbon dioxide takes place according to the above equilibrium equation especially in the descending charge when it has cooled below the active cyanid-forming temperatures. Here, 7 the damage is apparently caused by the formation of much carbon dioxide by reason of the comparatively low temperature and by the extended contact surface of the briquets; and, this is made worse by the fact that the temperature is too low for the alkaline decomposition products to be converted back into cyanids. In spite of this, however, a tube of the above mentioned size will yield over 100 pounds of sodium cyanid in 24 hours under the conditions described.

The above troubles can be overcome by introducing the producer gas, or the like, at the base of the heat zone in the furnace itself in any suitable manner and the tube or other receptacle in which the producer gas, or the like, is generated may also be in the cyanid furnace itself, thus giving the advantage of the use of air, as in Experiment 11, and highly preheated producer gas, combined with the advantages which reside in a continuously acting furnace.

While I have specifically mentioned certain free nitrogen containing gases, I do not desire to be limited to these, since I am aware that many commercial waste gases, such as those from a blast furnace, may be used instead of air or producer gas in effectuating my process. In the appended claims such an expression as "free nitrogen" is hence to be regarded as of sufficient breadth to cover free nitrogen no matter from what suitable source supplied.

Drawings—Second Sheet.—Fig. 5 somewhat diagrammatically shows a suitable furnace adapted for the carrying out of my process with, for example, producer gas. The tube or retort 35 in which the briquets (or other suitable form of cyanid producing charge) are placed, is shown to the right. 110 This tube is preferably enlarged at 36 so that the producer gas entering from a tube 37 can pass freely into the descending stream of briquets 38. Coke 39 is fed from a gas tight hopper 40 into a tube 41 by means of 115 a screw or other conveyer 42; and tube 41 is further connected with an air tight receptacle 43 for receiving the ashes 44 resulting from the combustion of the descending column of coke in the tube 41. A suitable conveyer 45 may be used to deliver said ashes to said receptacle 43. A short cross tube 46 connects the top of tube 41 with the top of tube 37 and a second such tube or conduit 47 connects the tube 37, at substantially the 120 bottom thereof, with the top of the enlarged part 36 of the retort 35. When the furnace is in operation, a current of air, entering at 48, meets the descending charge of hot coke in pipe 41 at the base of the heat zone and 125

there burns said coke to form producer gas and ashes. The latter, while being removed by conveyer 45, preheats the incoming air while the producer gas passes up through 5 the pipe 41 and thence down through the incandescent coke 49 in pipe 37, to the connection 47, whence a portion at least thereof enters and ascends through retort 35. Coke upon heating may give off moisture and 10 other oxygen containing materials and hence the continuous introduction of fresh coke at the top of pipe 41 would contaminate the producer gas with these oxygen-containing volatile products. The incandescent coke in 15 pipe 37, however, serves to decompose such volatile products before they can enter the retort 35. As the coke in the tube or like receptacle 37 is used simply as a purifier, it lasts a long time without renewal. I have 20 indicated by arrows the direction of the gas currents through the apparatus shown, and have broken away sections of the pipes and conveyers so as to better diagrammatically indicate the nature of the contents thereof. 25 In both pipes 41 and 35, it will be observed, the incoming gas is introduced substantially at the base of the heat zone; a feature of great advantage both in so far as the formation and heating of the producer gas is concerned and in that it overcomes the troubles 30 which, in the absence of this provision or its equivalent, are attendant upon the use of commercial producer gas or the like. The bottom of the retort 35 below the suitably 35 heated furnace 50, is, it will be observed air cooled, as in the preceding case: but other means for cooling may be utilized. The briquets or the like may be introduced into the retort 37 by means of a screw conveyer 40 51, also substantially as in the previously described apparatus, and the treated briquets delivered by the conveyer 52, corresponding to conveyer 15, may be suitably disposed of as in the form of apparatus previously described. I prefer, in this mode of 45 conducting my process, to provide an elongated hopper 53 as a reservoir from which are fed the briquets to the retort proper, and the gases ascending from the latter pass 50 up through said hopper to preheat the briquets therein as in the preceding case. As the carbon-monoxid formed in the retort passes up into the cooler upper parts of the briquet conveying conduit of which said 55 retort and hopper form parts, the lower temperature permits the conversion of a very considerable amount of said gas to carbon-dioxid as per equation 1: this action being evidently greatly favored, as previously 60 stated, by the catalytic iron-carbon (or equivalent) surface in the briquets. The apparatus shown in Fig. 5 also allows us to use a large excess of producer gas or its equivalent and to thus supply most or even 65 practically all of the heat necessary for

cyanid production. Thus a substantially pure mixture of carbon monoxid and nitrogen may be drawn off from the bottom of the receptacle 37 through a pipe 54 and delivered to the retort 35 above the reaction 70 zone through the connection 55. The connection 47 should, of course, be so proportioned, or the conduit therein otherwise so controlled, as to permit of the delivery of a proper amount of the gaseous mixture there-through to the base of the reaction zone despite this withdrawal of a considerable portion of the gas descending pipe 37 through pipe 54. Provision may also be made for the introduction of suitable carbon-monoxid 75 or carbon-monoxid and nitrogen containing gases from an extraneous source, such as, for example, a gas producer or blast furnace: such gases being delivered from pipe 56 direct through pipe 54 and connection 47 to the base of the reaction zone or through pipe 55 to the retort above said zone, or to the connection 46 via a pipe 57 and thence through the incandescent-coke containing receptacle 37, according to the nature and condition of said gases and the requirements of the cyanid forming reaction. Various combinations of these gas entries and the regulation of the flow of gas through the several pipes is controlled by the respective valves 58, 59, 60 and 61. It is thus possible to not only conserve heat but, further, to deposit enough carbon, in especially good condition, upon and around the catalytic 80 surface in the pores of the briquets, to make up or even more than make up for the carbon removed from the charge by the cyanid formation according to equation 3. In all cases, of course, where such deposition of carbon from the conversion of carbon monoxid to the dioxid is to be effected the briquet mass in the upper portion of the retort and in the conveyer 51 and hopper 53 (if the carbon is to be deposited in the latter) should be maintained, by extraneously supplied heat if necessary, at a temperature sufficient to permit of the dioxid-forming reaction taking place effectively. This temperature should preferably be in the neighborhood of 500° C. to 600° C. This procedure, in which the briquets, to be used in the subsequent cyanogen-compound-forming reaction, act in a peculiarly advantageous catalytic manner, makes it possible to supply carbon from gases containing carbon monoxid to produce an ashless carbon in very finely divided form and immediately and initially, so to speak, very closely incorporated in or associated with the iron or like catalyst employed. This mode of procedure is of especial value in case the cyanid is removed from the solid residues of the reaction by distillation, as, for example, in my said application Serial No. 737,368, and it also prevents contamination of the cyanid 85 90 95 100 105 110 115 120 125 130

or the like with silicates, aluminates, etc., when lixiviation is employed.

- The expression "vapor constituting the source of a metal adapted to act as the base of a cyanogen compound", used in certain of the claims, is to be regarded as of sufficient breadth to cover not only alkali carbonate or a like acting compound or compounds, but also sodium vapor or its equivalent. The molecules of this vapor when supplied by the volatilization of the sodium carbonate embodied in the briquets or the like, have but relatively extremely short distances to travel after liberation before they impinge against some portion of the ramified and greatly extended catalytic solution surface which permeates the mass of the briquets. In fact the briquets described, the walls of each of the pores thereof are in large part composed of the carbon dissolving material and the remainder of such walls largely consist of carbon and the said sodium carbonate; the latter serving not only as the source of said vapor but further, as previously intimated, as a binder for the carbon and catalytic material, whereby to hold the carbon so closely in contact with said material as to permit of the constant renewal of the carbon in solution therein as the latter is removed by the cyanid forming reaction. It is largely for this reason, too, that care in the temperature regulation must be exercised in order to preserve not only the catalytic iron, for example, in proper condition, avoiding sintering thereof which destroys its extended surface; but further to avoid unduly heating portions of the bulk of conglomerate being treated in such fashion as to cause an unequal consumption or even wasteful volatilization of the sodium carbonate, or equivalent, binder, which would permit of the subsequent disintegration of the briquets at such portions in the manner above set forth, even despite the cooling of the solid residues by the relatively cool nitrogen current or by extraneous means, or both.
- In certain of the appended claims it is specified that there is used in the process a metal or element which is capable of dissolving carbon, and where in such claims it is not specifically stated that the carbon participating in the reaction is in solution in such metal or element, said claims are to be regarded as of sufficient breadth to cover said carbon whether in solution in or in combination with said metal or element. Thus, iron is capable of dissolving carbon but when the reaction is effected the carbon may be (and preferably is) in solution therein: or it may be combined therewith to form a carbid. Where, also, in certain of the other claims it is specified that said metal or element is capable of combining with carbon, such expression is intended to

cover not only carbid forming metals, or the like, but such element or metal already combined with carbon, as in a carbid, and further metals, such as iron, which are capable of dissolving carbon or which may have carbon already in solution therein; the word "combining" being used as a generic term for all forms of chemical combination or solution, of the classes in question. Still further, where reference to the catalyst is omitted in any of the claims I desire it to be understood that such omission is intentional; so that in such cases the catalyst, iron, or the like, is not to be read into said claims. Finally, I desire to point out that by means of the foregoing process involving the conversion of carbon monoxide generated in the process, to carbon dioxide, it is possible to obtain argon from the atmosphere very economically. Thus carbon containing gases which issue from the cyanid forming mass may be removed, e. g., by oxidizing them completely to carbon dioxide and then absorbing the latter in any suitable known manner. This hence gives an economical method of separating the inert gases, principally argon, from atmospheric nitrogen through the removal of the latter during the course of the cyanid forming process. This latter process may be repeated with the residue, and in any case the residual gases will become enriched in argon.

Having thus described my invention what I claim is:

1. The process of fixing nitrogen which comprises passing a current of gaseous matter, a portion at least of which is free nitrogen, substantially evenly through the pores and interstices of a relatively large bulk of briquetted material which includes carbon and an element capable of dissolving carbon, said element being present in said briquetted material in such form as to present an extended catalytic surface to said gaseous matter, said briquetted material also having an initially combined base-forming element therein which is capable of being combined with the carbon in said surface and with said nitrogen to form a cyanogen compound of said base-forming element, and effecting a reaction in which participate said free nitrogen, carbon and base-forming element, to form said cyanogen compound.

2. The process of fixing nitrogen which comprises passing a current of gaseous matter, a portion at least of which is free nitrogen, through the pores and interstices of a relatively large bulk of briquetted material which includes carbon and an element capable of dissolving carbon, said element being present in said briquetted material in such form as to present an extended catalytic surface to said gaseous matter, said briquetted material also having an initially combined base-forming element therein

- which is capable of being combined with the carbon in said surface and with said nitrogen to form a cyanogen compound of said base-forming element and effecting a 5 reaction in which participate said free nitrogen, carbon and base forming element, to form said cyanogen compound, the said bulk of material being subject during the course of the operation to a force adapted 10 to compact the same and prevent the formation of conduits therein through which the gaseous matter may too freely escape.
3. The process of fixing nitrogen which 15 comprises, passing a current of gaseous matter, a portion at least of which is free nitrogen, under pressure substantially evenly through the pores and interstices of a relatively large bulk of material which includes 20 carbon and an element capable of dissolving carbon, said element being present in said material in such form as to present an extended catalytic surface to said gaseous matter, said material also having an initially 25 combined base-forming element therein which is capable of being combined with the carbon in said surface and with said nitrogen to form a cyanogen compound of said base-forming element, and effecting 30 a reaction, at a temperature of about 1000° C., in which participate said free nitrogen, carbon and base-forming element, to form said cyanogen compound.
4. The process of fixing nitrogen which 35 comprises subjecting a porous bulk of material which includes carbon, an element capable of dissolving carbon and a second element capable of acting as the base of a cyanogen compound under the conditions of 40 the operation, to the action of heat, and so disposing said bulk of material and applying the heat thereto as to insure an equable distribution of the latter throughout a reaction zone in said bulk of material in 45 which is present an extended surface of said carbon dissolving element, passing a current of gaseous matter, a portion at least of which is free nitrogen, under pressure substantially evenly through the pores of said 50 material in said zone and thereby effecting a reaction in which actively participate the said carbon, free nitrogen and said second mentioned element, to form said cyanogen compound.
5. The process of fixing nitrogen which 55 comprises subjecting a porous bulk of briqueted material which includes carbon, an element capable of dissolving carbon and a second element capable of acting as the base 60 of a cyanogen compound under the conditions of the operation, to the action of heat, and so disposing said bulk of briqueted material and applying the heat thereto as to insure an equable distribution of the latter throughout a reaction zone in said bulk 65 of briqueted material in which is present an extended surface of said carbon dissolving element, passing a current of gaseous matter, a portion at least of which is free nitrogen, under pressure substantially evenly through the pores of said material in said zone and thereby effecting a reaction in which actively participate the said carbon, free nitrogen and said second mentioned elements, to form said cyanogen compound.
6. The process of fixing nitrogen which 70 comprises subjecting a porous bulk of material which includes carbon, an element capable of dissolving carbon and a second element capable of acting as the base of a cyanogen compound under the conditions of the operation, to the action of heat, and so disposing said bulk of material and applying the heat thereto as to insure an equable 75 distribution of the latter throughout a reaction zone in said bulk of material in which is present an extended surface of said carbon dissolving element, passing a current of gaseous matter, a portion at least of which is free nitrogen, under pressure substantially evenly through the pores of said material in said zone and thereby effecting a reaction in which actively participate the said carbon, free nitrogen and said second mentioned elements, to form said cyanogen compound.
7. The process of fixing nitrogen which 80 comprises subjecting a porous bulk of material which includes carbon, an element capable of dissolving carbon and a second element capable of acting as the base of a cyanogen compound under the conditions of the operation, to the action of heat, and so disposing said bulk of material and applying the heat thereto as to insure an equable 85 distribution of the latter throughout a reaction zone in said bulk of material in which is present an extended surface of said carbon dissolving element, passing a current of gaseous matter, a portion at least of which is free nitrogen, under pressure substantially evenly through the pores of said material in said zone and thereby effecting a reaction in which actively participate the said carbon, free nitrogen and said second mentioned elements, to form said cyanogen compound, and causing successive portions of said material to advance 90 through said reaction zone.
8. The process of fixing nitrogen which 95 comprises subjecting a porous bulk of material which includes carbon, an element capable of dissolving carbon and a second element capable of acting as the base of a cyanogen compound under the conditions of the operation, to the action of heat, and so disposing said bulk of material and applying the heat thereto as to insure an equable 100 distribution of the latter throughout a reaction zone in said bulk of material in which is present an extended surface of said carbon dissolving element, passing a current of gaseous matter, a portion at least of which is free nitrogen, under pressure substantially evenly through the pores of said material in said zone and thereby effecting a reaction in 105 which actively participate the said carbon, free nitrogen and said second mentioned elements, to form said cyanogen compound, and causing successive portions of said material to advance through said reaction zone.
9. The process of fixing nitrogen which 110 comprises subjecting a porous bulk of material which includes carbon, an element capable of dissolving carbon and a second element capable of acting as the base of a cyanogen compound under the conditions of the operation, to the action of heat, and so disposing said bulk of material and applying the heat thereto as to insure an equable 115 distribution of the latter throughout a reaction zone in said bulk of material in which is present an extended surface of said carbon dissolving element, passing a current of gaseous matter, a portion at least of which is free nitrogen, under pressure substantially evenly through the pores of said material in said zone and thereby effecting a reaction in which actively participate the said carbon, free nitrogen and said second mentioned elements, to form said cyanogen compound, and causing successive portions of said material to advance through said reaction zone.
10. The process of fixing nitrogen which 120 comprises subjecting a porous bulk of material which includes carbon, an element capable of dissolving carbon and a second element capable of acting as the base of a cyanogen compound under the conditions of the operation, to the action of heat, and so disposing said bulk of material and applying the heat thereto as to insure an equable 125 distribution of the latter throughout a reaction zone in said bulk of material in which is present an extended surface of said carbon dissolving element, passing a current of gaseous matter, a portion at least of which is free nitrogen, under pressure substantially evenly through the pores of said material in said zone and thereby effecting a reaction in which actively participate the said carbon, free nitrogen and said second mentioned elements, to form said cyanogen compound.

distribution of the latter throughout a reaction zone in said bulk of material in which is present an extended surface of said carbon dissolving element, passing a current of 5 gaseous matter, a portion at least of which is free nitrogen, under pressure substantially evenly through the pores of said material in said zone and thereby effecting a reaction in which actively participate the said carbon,

10 free nitrogen and said second mentioned elements, to form said cyanogen compound, and causing successive portions of said material to advance through said reaction zone while preheating said portions previous to 15 their entrance into said zone.

9. The process of fixing nitrogen which comprises subjecting a porous bulk of material which includes carbon, an element capable of dissolving carbon and a second element capable of acting as the base of a cyanogen compound under the conditions of the 20 operation, to the action of heat, and so disposing said bulk of material and applying the heat thereto as to insure an equable distribution of the latter throughout a reaction zone in said bulk of material in which is present an extended surface of said carbon dissolving element, passing a preheated current 25 of gaseous matter, a portion at least of which is free nitrogen, under pressure through the pores of said material in said zone and thereby effecting a reaction in which actively 30 participate the said carbon, free nitrogen and said second mentioned element, to form 35 said cyanogen compound.

10. The process of fixing nitrogen which includes forming an extended catalytic solution surface comprising carbon dissolved in a metal in the solid phase which is capable of rendering said carbon reactive for participation in the ensuing reaction, and feeding the so dissolved carbon by gravity through a heated reaction zone, together with a substance which is capable of being vaporized and of acting as the source of a metal adapted to become the base of a cyanogen compound formed by said reaction, and supplying preheated free nitrogen to said zone to thereby form said cyanogen compound.

11. The process of fixing nitrogen which includes forming an extended catalytic solution surface comprising carbon dissolved in a metal in the solid phase which is capable of rendering said carbon reactive for participation in the ensuing reaction, and feeding the so dissolved carbon by gravity through a heated reaction zone, together with a substance which is capable of being vaporized and of acting as the source of a 55 metal adapted to become the base of a cyanogen compound formed by said reaction, and supplying preheated free nitrogen to said zone equally throughout substantially the extent thereof to thereby form said cyanogen compound.

12. The process of fixing nitrogen which includes forming an extended catalytic solution surface comprising carbon dissolved in a metal in the solid phase which is capable of rendering said carbon reactive for participation in the ensuing reaction, and feeding the so dissolved carbon by gravity into a heated reaction zone, together with a substance which is capable of acting as a source of a metal adapted to become the base of a 70 cyanogen compound formed by said reaction, supplying free nitrogen equally to said zone to thereby form said cyanogen compound, and preserving substantially intact and effective said solution surface by temperature 75 regulation while supplying additional carbon thereto as needed.

13. The process of fixing nitrogen which comprises subjecting reactive carbon, dissolved in a metal in the solid phase presenting an extended catalytic solution surface, to contact with preheated free nitrogen and a substance capable of yielding, during the course of the ensuing reaction, a metal adapted to act as the base of a cyanogen 80 compound stable at the temperature of the operation, effecting said reaction through the intermediacy of heat, and removing the residues from the zone of said reaction, directly thereafter.

14. The process of fixing nitrogen which comprises subjecting preheated reactive carbon, combined with a metal in the solid phase presenting an extended catalytic solution surface, to contact with preheated 90 free nitrogen and a substance capable of yielding, during the course of the ensuing reaction, a metal adapted to act as the base of a cyanogen compound stable at the temperature of the operation, effecting said reaction through the intermediacy of heat, and removing the residues from the zone of said reaction, directly thereafter.

15. The process of fixing nitrogen which comprises subjecting reactive carbon, combined with a metal in the solid phase presenting an extended catalytic solution surface, to contact with preheated free nitrogen and a substance capable of yielding, during the course of the ensuing reaction, a metal 100 adapted to act as the base of a cyanogen compound stable at the temperature of the operation, effecting said reaction through the intermediacy of heat, and removing the residues from the zone of said reaction, directly thereafter.

16. The process of fixing nitrogen which comprises forming porous briquets throughout the pores of which is present an extended catalytic surface of metal capable of rendering carbon reactive for participation in the ensuing reaction, said briquets also including carbon and a compound of a metal capable of acting as the base of a cyanogen compound to be formed by said reaction,

said compound of said metal adapted in part at least to act as a binder for the remaining material of said briquets, preheating said briquets, and subjecting the same while hot to the action of free nitrogen, whereby to form said cyanogen compound.

17. The process of fixing nitrogen which comprises forming porous briquets throughout the pores of which is present an extended catalytic surface of metal capable of rendering carbon reactive for participation in the ensuing reaction, said briquets also including carbon and a compound of a metal capable of acting as the base of a cyanogen compound to be formed by said reaction, said compound of said metal adapted in part at least to act as a binder for the remaining material of said briquets, preheating said briquets, subjecting the same while hot to the action of free nitrogen, whereby to form said cyanogen compound, and preserving substantially intact, by temperature regulation, the said briquets and the solution surface therein.

18. The process of fixing nitrogen which includes continuously supplying to a heated reaction zone, porous briquets, comprising a ramified and extended catalytic solution surface of a metal capable of rendering carbon reactive for participation in the ensuing reaction said surface together with carbon constituting in large part the walls of the pores in said briquets, rendering said briquets plastic by heat in said zone while maintaining the pores thereof accessible to gaseous and vaporous matters, and effecting an impingement of free nitrogen molecules together with those of a vapor constituting the source of a metal adapted to act as the base of a cyanogen compound, to be formed in said reactive zone, against said solution surface in said pores, whereby to form said cyanogen compound.

19. The process of fixing nitrogen which includes continuously supplying to a heated reaction zone, preheated porous briquets, comprising a ramified and extended catalytic solution surface of a metal capable of rendering carbon reactive for participation in the ensuing reaction said surface together with carbon constituting in large part the walls of the pores in said briquets, rendering said briquets plastic by heat in said zone while maintaining the pores thereof accessible to gaseous and vaporous matters, and effecting an impingement of free nitrogen molecules together with those of a vapor constituting the source of a metal adapted to act as the base of a cyanogen compound, to be formed in said reactive zone, against said solution surface in said pores, whereby to form said cyanogen compound.

20. The process of fixing nitrogen which includes continuously supplying to a heated reaction zone, porous briquets, comprising a

ramified and extended catalytic solution surface of a metal capable of rendering carbon reactive for participation in the ensuing reaction, said surface together with carbon constituting in large part the walls of the pores in said briquets, rendering said briquets plastic by heat in said zone while maintaining the pores thereof accessible to gaseous and vaporous matters, and effecting an impingement of previously and separately preheated free nitrogen molecules together with those of a vapor constituting the source of a metal adapted to act as the base of a cyanogen compound, to be formed in said reactive zone, against said solution surface in said pores, whereby to form said cyanogen compound.

21. The process of fixing nitrogen which includes continuously supplying to a heated reaction zone, preheated porous briquets comprising a ramified and extended catalytic solution surface of a metal capable of rendering carbon reactive for participation in the ensuing reaction said surface together with carbon constituting in large part the walls of the pores in said briquets, rendering said briquets plastic by heat in said zone while maintaining the pores thereof accessible to gaseous and vaporous matters, and effecting an impingement of previously and separately preheated free nitrogen molecules together with those of a vapor constituting the source of a metal adapted to act as the base of a cyanogen compound, to be formed in said reactive zone, against said solution surface in said pores, whereby to form said cyanogen compound.

22. The process of fixing nitrogen which includes continuously supplying to a heated reaction zone a column of porous briquets comprising a ramified and extended catalytic solution surface of a metal capable of rendering carbon reactive for participation in the ensuing reaction, said surface constituting in large part the walls of the pores of said briquets and the remainder of said walls being composed principally, at least, of carbon and a compound the base of which is a metal capable of forming the base of a stable cyanogen compound during the course of the reaction effected in said zone, maintaining said pores accessible to gaseous and vaporous matters, and flowing a current of gaseous matter consisting, in part at least, of free nitrogen through said reaction zone, whereby to form said cyanogen compound.

23. The process of fixing nitrogen which comprises subjecting a porous bulk of briquetted material which includes carbon, an element capable of combining with said carbon and a second element capable of acting as the base of a cyanogen compound under the conditions of the operation, to the action of heat in a reaction zone in said material in

which is present and maintained an extended carbon containing catalytic surface of said first element, equably distributing said heat in said zone and introducing a current of gaseous matter, a portion at least of which is free nitrogen, at substantially the base of said zone, whereby to effect a reaction in which the carbon in solution in said surface, said free nitrogen and said second element actively participate to form said cyanogen compound.

24. The process of fixing nitrogen which comprises subjecting a hot moving mass comprising briquets in each of which is present an extended surface composed of carbon in combination with a catalyst capable of rendering said carbon reactive, to contact with free nitrogen, while vaporizing in said mass a substance which is capable of yielding, under the just recited conditions, an element adapted to act as the base of a cyanogen compound stable at the temperature of the operation, effecting a reaction in which participate said carbon, nitrogen and element, and thereafter lowering the temperature of the reactive mass during a further movement thereof, whereby to substantially preserve said briquets.

25. The process of fixing nitrogen which comprises so subjecting a hot moving mass of diminutive porous briquets, in which mass, as a whole, is present an extended surface composed of carbon in combination with a catalyst capable of rendering said carbon reactive, to contact with free nitrogen, as to freely introduce said nitrogen into said pores while the latter contain an element in condition to react with said nitrogen and with said carbon to form a cyanogen compound the base of which is said element, and regulating the temperature of said moving mass throughout the extent thereof so as to preserve said briquets substantially intact.

26. The process of fixing nitrogen which comprises so subjecting a hot moving mass of porous briquets, in which mass, as a whole, is present an extended surface composed of carbon in combination with catalyst capable of rendering said carbon reactive, to contact with free nitrogen, as to freely introduce said nitrogen into said pores while the latter contain an element in condition to react with said nitrogen and with said carbon to form a cyanogen compound the base of which is said element, and regulating the temperature of said moving mass throughout the extent thereof so as to preserve said briquets substantially intact.

27. The process of fixing nitrogen which comprises establishing a heated non-sintering reaction zone and moving a mass of catalytic briqueted material, constituents of which are capable of reacting with free nitrogen to form a cyanogen compound,

through said zone under cyanogen compound forming conditions, lowering the temperature of said briqueted material after it leaves said zone, supplying the free nitrogen needed for the cyanogen-compound-forming reaction mixed with carbon monoxid and introducing such gaseous mixture into said mass of briqueted material at points in the course of the latter when the temperature of said material has not been lowered sufficiently to permit of the conversion by an equilibrium reaction of any considerable portion of said monoxid to carbon dioxid.

28. The process of fixing nitrogen which comprises establishing a heated reaction zone and moving a mass of briqueted material constituents of which are capable of reacting with free nitrogen to form a cyanogen compound, through said zone under cyanogen compound forming conditions, lowering the temperature of said briqueted material after it leaves said zone, supplying the free nitrogen needed for the cyanogen-compound-forming reaction mixed with carbon monoxid, introducing such gaseous mixture into said mass of briqueted material at points in the course of the latter where the temperature of said material has not been lowered sufficiently to permit of the conversion by an equilibrium reaction of any considerable portion of said monoxid to carbon dioxid and converting said carbon monoxid to carbon dioxid within said mass at points where said dioxid is unable to deleteriously affect the cyanogen compound formed.

29. The process of fixing nitrogen which comprises establishing a heated reaction zone and therein effecting a reaction in which participate oxygen, reactive carbon, free nitrogen and an element capable of acting as the base of a cyanogen compound which shall be stable at the temperature of said zone, whereby to form carbon monoxid and said cyanogen compound, and thereafter so converting said carbon monoxid to carbon dioxid as to permit of the utilization of the heat evolved by said last reaction, in said reaction zone.

30. The process of fixing nitrogen which includes forming a mixture of atmospheric nitrogen and an oxid of carbon, purifying said mixture by bringing it into contact with incandescent carbonaceous matter to eliminate deleterious impurities therefrom, introducing the resulting gases into a reaction zone in which are present dissolved carbon and a compound of a metal capable of acting as the base of a cyanogen compound to be formed in said zone, equably distributing said resulting gases through said zone, substantially equably heating the materials therein, whereby to form said cyanogen compound, cooling the solid residues

of the cyanogen-compound-forming reaction and deterring the said oxid of carbon from gaining access to said cooled residues.

31. The process of fixing nitrogen which 5 includes forming a mixture of atmospheric nitrogen and an oxid of carbon, introducing said mixture into a reaction zone in which are present dissolved carbon and a compound of a metal capable of acting as the 10 base of a cyanogen compound to be formed in said zone, equably distributing said mixture through said zone, substantially equably heating the materials therein, whereby to form said cyanogen compound, cooling 15 the solid residues of the cyanogen-compound-forming reaction, and preventing the said oxid of carbon from gaining access to said cooled residue.

32. The process of fixing nitrogen which 20 comprises subjecting a stream of porous briquets in which are present finely divided carbon and a carbonate of a metal adapted to act as the base of a cyanogen compound to be formed during the course of the process and which carbonate acts, in part at least, as a binder for the briquetted material, to the action of free nitrogen in a heated reaction zone, rendering said briquets plastic by heat, effecting a reaction in said zone 25 yielding said cyanogen compound and carbon monoxid, and lowering the temperature of said briquets after said reaction has been effected therein, whereby to preserve the integrity of said briquets while conducting 30 said carbon monoxid away from said zone in a direction substantially contrary to that in which said stream of briquets is moving.

33. The process of fixing nitrogen which comprises subjecting a stream of porous 40 briquets in which are present finely divided carbon and an oxygen compound of a metal adapted to act as the base of a cyanogen compound to be formed during the course of the process and which oxygen compound 45 acts, in part at least, as a binder for the briquetted material, to the action of free nitrogen in a heated reaction zone, rendering said briquets plastic by heat, effecting a reaction in said zone yielding said 50 cyanogen compound and carbon monoxid, and lowering the temperature of said briquets after said reaction has been effected therein, whereby to preserve the integrity of said briquets while conducting said carbon 55 monoxid away from said zone in a direction substantially contrary to that in which said stream of briquets is moving.

34. The process of fixing nitrogen which comprises treating a briquetted porous mass, 60 in the pores of which is present a solvent for carbon, with a carbonaceous gas, at a temperature at which said gas is at least in part unstable, whereby to deposit carbon in

said pores and dissolve the same, and reacting upon said dissolved carbon, at a higher 65 temperature, with free nitrogen and a metal capable of acting as the base of a stable cyanogen compound, to form said cyanogen compound.

35. The process of fixing nitrogen which 70 comprises, treating a porous mass which contains a compound of a metal which is capable of acting as the base of a stable cyanogen compound, to establish two reaction zones therein, subjecting said mass in 75 one zone to a carbonaceous gas and depositing carbon from said gas in the pores of the mass within said zone, and then effecting a cyanogen - compound - forming reaction in said second zone, in which participate said 80 carbon, free nitrogen and said metal.

36. The process of fixing nitrogen which comprises, treating a porous mass which contains a compound of a metal which is capable of acting as the base of a stable 85 cyanogen compound, to establish two reaction zones therein, subjecting said mass in one zone to a carbonaceous gas and depositing carbon from said gas in the pores of the mass within said zone, moving said mass 90 from said first to said second zone by gravity while elevating the temperature thereof, and effecting a cyanogen-compound-forming reaction in said second zone, in which participate said carbon, free nitrogen and 95 said metal.

37. The process of fixing nitrogen which comprises intimately mixing a carburizable metal in finely divided condition with two substances one of which is capable of supplying carbon to said metal to carbonize the same and the other of which is an oxygen compound of an element capable of acting as the base of a cyanogen compound, pressing said mixture into briquets to establish efficient contact conditions between said carburizable metal and said substances, carburizing said metal in part from carbon supplied from said carbon supplying substance and in part by passing carbon-monoxid thereover at a temperature at which a considerable part of said monoxid will be converted into carbon dioxid and thereby deposit carbon in said briquets, whereby to reduce the quantity of ash which may be 100 formed therein, and effecting a cyanogen-compound-forming reaction which removes carbon from said carburized metal, by treating said briquets with free nitrogen in a 105 heated reaction zone.

In testimony whereof I have affixed my signature, in the presence of two witnesses.

JOHN E. BUCHER.
